UNITED STATES PATENT OFFICE.

FRANK CRIST, OF COLUMBUS, OHIO.

PAWL-AND-RATCHET MECHANISM.

1,246,555.

Specification of Letters Patent. Patented Nov. 13, 1917.

Application filed August 17, 1916. Serial No. 115,483.

To all whom it may concern:

Be it known that I, FRANK CRIST, a citizen of the United States, and a resident of Columbus, in the county of Franklin and State of Ohio, have invented certain new and useful Improvements in Pawl-and-Ratchet Mechanism; and I do hereby declare the following to be a full, clear, and exact description of the invention, such as will enable others skilled in the art to which it appertains to make and use the same.

My invention relates to an improvement in pawl and ratchet mechanism designed particularly for use with means for supporting drills on or against the work to be drilled and is an improvement on the construction disclosed in my Patent No. 1,184,829 granted to me May 30th, 1916, and it consists in the parts and combinations of parts as will be more fully explained and pointed out in the claims.

In the accompanying drawings, Figure 1 is a view in side elevation of my improved device; Fig. 2 is a view in edge elevation of the same, and Figs. 3, 4 and 5 are views in section showing the pawl in its several positions.

1 represents a bit which in the present instance is actuated by air, but which may be driven by electricity or other suitable means, and 2 is a chamber carrying the motor for actuating the bit. Secured to one end of the chamber or drill casing, on the side opposite that from which the bit projects, is a centrally located stud 3 threaded externally, and inclined arms 4 supporting the ring 5 at their outer ends, the ring being concentric with the stud 3 for supporting the frame 6.

40 This frame 6 is provided with a threaded socket to engage the stud, and is of a size and shape to snugly fit within and be supported by the ring 5 when the parts are assembled. It is bifurcated at its opposite 45 end to receive and support the drum 7 which is mounted on the axle or pin 8 carried by the said frame. The drum 7 is preferably recessed as shown in Fig. 1 to receive the ends of the end links of the 50 chains 10, which are secured to the drum by the pin 9, and is provided at one or both ends, preferably both, with a ratchet wheel 11.

Both chains 10 leave the drum from the

same side, so that both will wind simultaneously in the same direction. Each is provided at its free end with a loop 12 having an opening 13 large enough for the passage of a chain 15, and with a slot 16 communicating with said opening and of a size to receive a chain link edgewise, so that by passing a chain 15 through the opening 13 and dropping a link into the slot 16, the chains 15 will be locked to chains 10, thus providing for close adjustment of the chain 55 so that comparatively little slack will have to be taken care of after the machine has been set up. The free end of each chain 15 carries a hook 17 for its attachment to the work to be drilled, or to any other fixed 60 object or objects adjacent to the work.

The frame 6 is slotted adjacent the point of bifurcation of the same as shown in Figs. 1 and 2 for the reception of the pawl 18 which is of a width sufficient to engage the teeth of both ratchet wheels 11 as clearly shown in Fig. 2. The cylindrical portion of the frame below the slot is made hollow for the stem 18^a of the pawl and for the spring 18^b, which latter rests at its lower 70 end on the shoulder 20 within the frame 6, and bears at its upper end against the shoulder 18^c on the stem of the pawl. The spring is always under tension and exerts a constant pressure tending to hold the 75 pawl in contact with the teeth of the ratchet wheel. The stem 18^a of the pawl passes through the spring, and carries at its lower end, at a point below the shoulder 20, a pin 21, the frame 6 being slotted as at 22 to 80 permit of the free up and down movements of said pin. This pin projects at its ends through the slot in the frame 6, and its ends rest in inclined slots 23 in the sleeve 24. This sleeve embraces the frame 6 and closes 85 the ends of the slot 22, and is normally retained against the shoulder 24^a on the frame by the spring 18^b, acting of course through the stem 18^a and pin 21.

From the foregoing it will be seen that 90 by giving the sleeve 24 a part turn, the pin 21 will be moved either up or down the inclined slots 23, thus carrying the pawl into or out of engagement with the teeth of the ratchet wheels. In Fig. 3 I have shown the 95 pawl in engagement with the ratchet wheels, and in Fig. 5 I have shown it withdrawn so that the drum and ratchet may freely turn

when applying the apparatus to a piece of work. Fig. 4 shows the movement of the pawl when turning the drum in a direction to wind the chains thereon.

5 Pivottally mounted on the pin or axle carried by the frame 6, is the handle 25 which is substantially identical in construction with the frame 6 except that the bifurcated end is widened to permit the free ends of 10 its arms to straddle the arms of frame 6. It is provided with a pawl 26 spring 27 pin 28 and sleeve 29 substantially identical with the pawl arrangement on frame 6 except that the sleeve 29 is not slotted, the pin 28, 15 being secured in holes in the sleeve so that by pulling upwardly or outwardly on the latter the pawl will be pulled away from the ratchet wheels, and when released will again be projected into contact with the 20 teeth on the ratchet wheel.

By pulling on the handle to the left (Fig. 1) the chains will be wound on the drum until all the slack has been taken up thus rigidly supporting the drill in proper position with relation to the work. The application or setting up of the drill can be readily and quickly accomplished by adjusting the chains as to length, and subsequently taking up the slack by rotating the 30 drum. The handle 25 may be of a weight sufficient to automatically turn the drum to take up the slack in the chains as the drill sinks into the work.

If the drill be boring upwardly the handle 25 may be turned to the right more than 90° so that its weight will turn the drum and take up the slack in the chains as the work progresses.

With this improvement the drill is supported by chains which are always under tension and the slack due to the penetration of the drill is automatically taken care of by the automatic or manual operation of the ratchet. It may be readily and quickly applied to any piece of work and be readily released after the hole has been drilled.

It is evident that many slight changes might be resorted to in the relative arrangement of parts shown and described without departing from the spirit and scope of my invention. Hence I would have it understood that I do not wish to confine myself to the exact construction and arrangement of parts shown and described, 55 but

Having fully described my invention

what I claim as new and desire to secure by Letters-Patent, is:—

1. In a pawl and ratchet mechanism, the combination of a frame carrying a ratchet wheel and a drum, a pawl having a sliding movement in said frame and adapted to engage the teeth of the wheel, a spring tending to normally hold the pawl in engagement with the wheel, a sleeve mounted to 60 rotate on the frame and provided with an inclined slot, a pin engaging the stem of the pawl with its ends in the slot in the sleeve, so that by turning the sleeve the pawl will be withdrawn and held out of 65 engagement with the teeth of the ratchet wheel, a handle pivoted to said frame and a longitudinally movable spring pressed pawl carried by said handle and adapted to engage the teeth of the ratchet wheel. 75

2. In pawl and ratchet mechanism, the combination of a frame carrying a ratchet wheel and a drum, a pawl mounted to slide in said frame, a spring embracing the shank of the pawl for forcing it toward the ratchet 80 wheel, a pin passing through the shank of the pawl and also through oblong slots in the frame, a sleeve mounted to turn on said frame and provided with oppositely disposed inclined slots to receive the ends of 85 the pin, a handle pivoted to the said frame, a spring pressed pawl carried by said handle, and a longitudinally movable sleeve mounted on the handle and connected with said spring pressed pawl for moving it out 90 of contact with the ratchet.

3. In pawl and ratchet mechanism the combination of a frame, a handle pivoted to the frame, a ratchet wheel mounted in the frame, a spring pressed pawl in the 95 frame and also one in the handle both of said pawls adapted to engage the ratchet wheel carried by the frame, a rotary sleeve having connection with one of said pawls for moving and holding it out of engagement with the ratchet and a sliding sleeve having connection with the other pawl for moving it out of engagement with the ratchet wheel. 100

In testimony whereof, I have signed this 105 specification in the presence of two subscribing witnesses.

FRANK CRIST.
